UNITED STATES PATENT OFFICE.

PETER JUNG, OF PERHAM, MINNESOTA.

MUSIC-LEAF TURNER.

SPECIFICATION forming part of Letters Patent No. 425,178, dated April 8, 1890.

Application filed October 29, 1889. Serial No. 328,531. (No model.)

To all whom it may concern:

Be it known that I, PETER JUNG, of Perham, in the county of Otter Tail and State of Minnesota, have invented a new and Improved 5 Music-Leaf Turner, of which the following is a full, clear, and exact description.

The object of the invention is to provide a new and improved music-leaf turner which is simple and durable in construction, can be 10 easily and quickly adjusted or set, and conveniently operated by a slight touch of the finger.

The invention consists of certain parts and details and combinations of the same, as will 15 be hereinafter fully described, and then pointed out in the claims.

Reference is to be had to the accompanying drawings, forming a part of this specification, in which similar letters of reference indicate 20 corresponding parts in all the figures.

Figure 1 is a perspective view of the improvement. Fig. 2 is an enlarged front view of the locking and releasing device. Fig. 3 is a sectional side elevation of the same, and Fig. 25 4 is a similar view of the same in a different position.

The improved music-leaf turner A is mounted on the usual music stand or back B, provided with an offset C, on which rests the 30 lower end of the book or leaves to be turned. In the middle of the offset C is pivoted a rod D, extending upward and adapted to engage a hook E, secured on the upper end of the back B. This rod D serves to hold the book or 35 loose sheets of music in place on the back.

On the back B, near its lower end, are secured the bearings F, in which are mounted a series of rods G, placed parallel with each other, as shown in Fig. 1. On the upper end 40 of each rod G is secured an arm H, extending at right angles to the rod G and provided with a bend H', to which is connected one end of a spring I, coiled on the upper end of the respective rod G, and secured by its other end 45 on the back B.

On the outer end of each arm H is secured an upwardly-extending arm J, adapted to engage the under side of the leaf to be turned. The said arm projects above the offset C, so 50 as to conveniently engage the respective leaf to be turned. Each of the arms H is guided,

when in said position, in a notched bracket K, secured to the back B on the right side of the same. Near this bracket K is arranged the locking and releasing device L, provided 55 with the casing N, secured on the back B, and in which is mounted to slide a bolt O, extending through the casing N at each end. The upper end O' of the bolt is adapted to pass over the series of arms H when the latter are 60 moved into a right-hand position, and the said end O' is adapted to release the arms successively, so that the latter swing by the action of the springs I into their left normal position, so as to carry along the leaves, the backs of 65 which they engage.

The bolt O is provided near its lower end with a number of notches O², placed equal distances apart and adapted to be engaged by an end P' of a flat spring P, secured on a finger-piece Q, projecting through a slot N' in the casing N. The finger-piece Q also supports a back plate Q', resting on top of the spring P, and a coil-spring R is adapted to press against said back plate Q', so as to hold the finger-piece Q' in an uppermost position—that is, at the upper end of the slot N'. On the top of the bolt O is held to slide a locking-plate S, on which rests the upper end P² of the spring P, said locking-plate projecting through the 70 upper end of the casing, and being provided on its outer end with an offset or flange adapted to be grasped by the operator to slide the locking-plate outward. On the lower end of the bolt O is formed a handle O³, 75 for conveniently moving the bolt whenever necessary, and near the upper end O' of the bolt is formed a shoulder O⁴, against which is adapted to abut a flange S' of the locking-plate S. 80

The operation is as follows: When the rod D is disengaged from its hook E, the book or a number of leaves are placed on the back B, resting with their lower edges on the offset C. The rod D is then passed through the 85 middle of the open book or leaves and fastened at its upper end to the hook E. The several leaves to be turned are placed successively between the arms J, and then the latter are all swung to the right against the tension 90 of the springs I, and there locked in place by the upper end O' of the bolt O passing over 95

the said arms H. The bolt O is manipulated in the following manner: In order to move the bolt upward, so that its upper end O' passes over the several arms H, it is necessary that the operator should press the locking-plate S into the position shown in Fig. 3, so that the lower end of the said locking-plate S engages the end P' of the spring P, thus lifting the said end P' out of contact with one of the notches O² of the bolt O, so that the latter can be shoved upward by the operator pressing on the flange or handle O³. When the bolt is in its uppermost position, as shown in Fig. 4, the operator grasps the flange S' of the locking-plate and pulls the latter outward until the flange S' rests against the shoulder O⁴ of the bolt O. By the outward movement of the locking-plate S the lower end P' of the spring P engages the lowermost one of the notches O². 10 When the operator now desires to turn the first leaf, he simply presses the finger-piece Q downward against the tension of the spring R, whereby the spring P with its end P' moves the bolt O downward a distance equal to the 15 space between two teeth, which distance corresponds to the length of the slot N'. This movement of the bolt O releases the uppermost arm H, so that the spring I of the latter swings the arm H to the left, carrying the leaf 20 along with it. As soon as the operator releases the pressure on the finger-piece Q, the latter is moved backward in its normal uppermost position by the spring R. This upward movement of the finger-piece Q carries along the 25 spring P, so that the next following one of the notches O² is engaged. The above-described operation is then repeated successively until all the arms H have swung to the left. 30 It is to be understood that the arms H are placed one above the other a distance corresponding to the distance between the teeth on the bolt O. Thus it will be seen that the device is very simple and durable in construction and can easily and quickly be set and 35 conveniently operated by a slight touch of the finger.

Having thus fully described my invention, I claim as new and desire to secure by Letters Patent—

40 50 1. In a music-leaf turner, the combination,

with spring-pressed arms mounted to swing, of a locking and releasing mechanism to lock and release successively the said arms, comprising a notched bolt mounted to slide over the said arms, a finger-piece for operating the said bolt, and a flat spring held on the said finger-piece and adapted to engage at one end the said notched bolt, substantially as shown and described. 55

2. In a music-leaf turner, the combination, with spring-pressed arms mounted to swing, of a locking and releasing mechanism to lock and release successively the said arms and comprising a notched bolt mounted to slide over the said arms, a finger-piece for operating the said bolt, a flat spring held on the said finger-piece and adapted to engage at one end the said notched bolt, and a second spring pressing on the said finger-piece, substantially as shown and described. 60

3. In a music-leaf turner, the combination, with spring-pressed arms mounted to swing, of a locking and releasing mechanism to lock and release successively the said arms and comprising a notched bolt mounted to slide over the said arms, a finger-piece for operating the said bolt, a flat spring held on the said finger-piece and adapted to engage at one end the said notched bolt, a second spring pressing on the said finger-piece, and a locking-plate held to slide on the said bolt and adapted to be engaged by the ends of the said flat spring, substantially as shown and described. 70

4. In a music-leaf turner, the combination, with a notched bolt mounted to slide in a casting, of a flat spring adapted to engage the said notched bolt, and a spring-pressed finger-piece for moving the said spring, substantially as shown and described. 80

5. In a music-leaf turner, the combination, with a notched bolt mounted to slide in a casting, of a flat spring adapted to engage the said notched bolt, a spring-pressed finger-piece for moving the said spring, and a locking-plate interposed between the said spring and the said bolt, substantially as shown and described. 90
